UNITED STATES PATENT OFFICE.

AMOS A. AMSTUTZ, OF BLUFFTON, OHIO.

SCREW-HOIST CLUTCH.

Application filed August 11, 1922. Serial No. 581,180.

To all whom it may concern:

Be it known that I, AMOS A. AMSTUTZ, a citizen of the United States, residing at Bluffton, in the county of Allen and State 5 of Ohio, have invented a new and useful Screw-Hoist Clutch, of which the following is a specification.

This invention aims to provide a simple means whereby, at the will of an operator, 10 a winding drum may be operated through the instrumentality of a worm, or otherwise.

It is within the province of the disclosure to improve generally and to enhance the utility of devices of that type to which the 15 invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from 20 the spirit of the invention.

In the accompanying drawings:—

Figure 1 shows in elevation, a device constructed in accordance with the invention; Figure 2 is an elevation showing a part of

30 the releasing means; Figure 3 is a longitudinal section wherein parts appear in elevation; Figure 4 is a transverse section showing a part of the releasing means; Figure 5 is a fragmental vertical section disclosing a 35 part of the releasing means; Figure 6 is a perspective view showing the member for operating the tongue; Figure 7 is an elevation wherein the device is viewed at right angles to the showing of Figure 1.

40 The numeral 1 marks an inverted U-shaped frame comprising arms 2 and 3. A suspension means 4 is assembled with the top of the frame 1. A shaft 5 is mounted in the lower ends of the arms 2 and 3 and has a reduced end 6 defining a shoulder 7.

45 A drum 8 is journaled on the reduced end of the shaft 5 and is held against sliding movement, longitudinally of the shaft, by the shoulder 7 and the arm 3 of the frame 1.

50 In its outer face, the drum 8 is supplied with a recess 9 wherein is located a coil spring 10, one end of the spring being secured to the drum and the other end of the spring being anchored in any suitable way 55 with respect to the frame 1. A flexible element 11, such as a chain, is secured at 12

to the periphery of the drum 8 and extends about the drum. The flexible element 11 is adapted to carry a weight which is to be lifted. The drum 8 has an inwardly projecting flange 14 provided with teeth 15.

A rotatable element 16, which may be a worm wheel having peripheral teeth 17, is journaled on the shaft 5 and has movement on the shaft longitudinally of the shaft. The rotatable element 16 has an inwardly projecting flange 18 provided with teeth 19 adapted to cooperate with the teeth 15 on the drum 8, the teeth 19 and 15 constituting a clutch connection between the rotatable member 16 and the drum 8. The peripheral teeth 17 of the rotatable element or worm wheel 15 mesh with a worm 20 carried by a shaft 21 journaled in a bearing 22 extended between the arms 2 and 3 of the frame 1, and in an offset bearing bracket 23 projecting inwardly from the arm 2 of the frame 1. The worm 20 is located between the bearing 22 and the bracket 23 and, thus, longitudinal movement of the shaft 21 is prevented. Any suitable means may be supplied for rotating the shaft 21. If desired, the shaft may be equipped at its outer end with a sprocket wheel 24 about which passes a looped sprocket chain 25.

The rotatable member or worm wheel 16 is provided with a hub 26 having a circumferential groove 27 in which fits the lower end of a spring tongue 28 secured at its upper end to the arm 2 of the frame 1 and extending downwardly in diverging relation with respect to the said arm. The tongue 28 has a projection 29 slidable in the arm 2 of the frame 1 and provided with a finger 30 located externally of the arm 2 and disposed parallel thereto.

In practical operation, when the clutch teeth 19 and 15 are interengaged, as shown in Figure 3, rotation imparted to the shaft 21 will be transmitted to the worm 20, the worm cooperating with the worm wheel 17—16 and rotating the worm wheel, motion being transmitted to the drum 8, and the flexible element being reeled thereon, since the drum is connected operatively to the rotatable member 16 through the instrumentality of the clutch teeth 19—15. It may be desirable to operate the drum 8 otherwise than by way of the worm wheel 16, and, under such conditions, the tongue 28 is moved to the right in Figure 3, the worm wheel 16 being carried to the right, and the

teeth 19 of the worm wheel being detached from the teeth 15 of the drum 8. Thereupon, the drum may be worked independently of the worm wheel. The purpose of 5 the spiral spring 10 is to offset the weight of the chain or flexible element 11 when the drum 8 is operated independently of the worm wheel 16, the spring 10 reacting to take up the flexible element 11 and to wind 10 the same on the drum 8. The construction of the device is such that the drum 8 may be detached from the worm wheel 16, thereby permitting a rapid rotation of the drum under any desired conditions.

15 Any preferred means may be employed for swinging the spring tongue 28 to the right in Figure 3. If desired, but not of necessity, a shaft 31 may be journaled in the arm 2 of the frame 1, the shaft being provided at its outer end with a transverse head 32, whereunto depending flexible elements 33 are attached. The shaft 31 carries an arm 34 provided with a wedge-shaped head 35. When one of the flexible elements 33 is 20 pulled upon, the head 35 enters between the finger 30 of the projection 29 and the arm 2, thereby moving the projection 29 outwardly, carrying with it the spring tongue 28. When the other of the flexible elements 33 is 25 drawn upon, the wedge-shaped head 35 retires from between the finger 30 and the arm 2, the tongue 28 returning, due to its resiliency, to the position shown in Figure 3, the rotatable element 16 being carried inwardly to engage with the drum 8.

What is claimed:—

1. In a device of the class described, an inverted U-shaped frame comprising side arms, a shaft carried by the side arms, a 40 wheel journaled on the shaft, a rotatable member journaled on the shaft, the wheel and the rotatable member having cooperating clutch elements, and the rotatable member being movable longitudinally of the shaft, the rotatable member having a circumferential groove, a spring tongue secured at one end to one side arm of the frame, the opposite end of the tongue being received in 45 the groove, the tongue constituting means for moving the rotatable member longitudinally of the shaft, thereby to cause the clutch elements to interengage, a projection on the tongue and slideable in said one arm, the projection being provided with a finger located externally of said arm and disposed about parallel thereto, a shaft journaled in said arm, a wedge-shaped member carried by the last-specified shaft and adapted to enter between the finger and said arm, a cross piece secured intermediate its ends to the last-specified shaft, and depending operating members connected to the ends of the cross-piece.

2. In a device of the class described, an inverted U-shaped frame comprising side 65 arms, a shaft carried by the side arms, a wheel journaled on the shaft, a rotatable member journaled on the shaft, the wheel and the rotatable member having cooperating clutch elements, and the rotatable member being movable longitudinally of the shaft, the rotatable member having a circumferential groove, a spring tongue secured at one end to one side arm of the frame, the opposite end of the tongue being received in 70 the groove, the tongue constituting means for moving the rotatable member longitudinally of the shaft, thereby to cause the clutch elements to interengage, a projection on the tongue and slideable in said one arm, the projection being provided with a finger located externally of said arm and disposed about parallel thereto, a shaft journaled in said arm, a wedge-shaped member carried by the last-specified shaft and adapted to enter between the finger and said arm, a cross piece secured intermediate its ends to the last-specified shaft, and depending operating members connected to the ends of the cross-piece.

2. In a device of the class described, an inverted U-shaped frame comprising side 65 arms, a shaft carried by the side arms, a wheel journaled on the shaft, a rotatable member journaled on the shaft, the wheel and the rotatable member having cooperating clutch elements, and the rotatable member being movable longitudinally of the shaft, the rotatable member having a circumferential groove, a spring tongue secured at one end to one side arm of the frame, the opposite end of the tongue being received in 70 the groove, the tongue constituting means for moving the rotatable member longitudinally of the shaft, thereby to cause the clutch elements to interengage, a projection on the tongue and slideable in said one arm, the projection being provided with a finger located externally of said arm and disposed about parallel thereto, and means mounted on the frame and under the control of an operator for disengaging said clutch elements, said means comprising a part adapted to enter between the finger and said arm of the frame.

In testimony that I claim the foregoing as my own, I have hereto affixed my signature in the presence of two witnesses.

AMOS A. AMSTUTZ.
